UNITED STATES PATENT OFFICE.

MADISON D. SHIPMAN, OF DE KALB, ILLINOIS.

BUTTON.

SPECIFICATION forming part of Letters Patent No. 352,270, dated November 9, 1886.

Application filed January 27, 1885. Serial No. 154,152. (No model.)

To all whom it may concern:

Be it known that I, MADISON D. SHIPMAN, a citizen of the United States of America, residing at De Kalb, in the county of De Kalb 5 and State of Illinois, have invented certain new and useful Improvements in Buttons, of which the following is a specification, reference being had therein to the accompanying drawings.

10 My invention relates more particularly to that class of separable buttons in which there is a tube in one of the parts adapted to receive a stud from the other part, through a slot in which tube a spring passes and enters a 15 groove or recess in the stud; and the invention consists in the peculiar arrangement and construction and combinations of parts herein-after more particularly described and claimed.

The accompanying drawings show my im- 20 provement on an enlarged scale, the better to show the parts.

In said drawings, Figure 1 is a vertical central section of my button in position for use. Fig. 2 is a reversed plan of the cap of the button 25 and its tube. Fig. 3 is a vertical section of the same before its attachment. Fig. 4 is a section of the stud before its attachment. Fig. 5 is a section of an eyelet used for fastening the stud. Fig. 6 is a section of a washer for fast- 30 ening the button. Fig. 7 is a modification of the mode of fastening the stud.

A represents the cap which forms substantially the top of the button proper, and is provided with a central tube, B, said cap and 35 tube being struck up in one piece, and preferably having the tube formed thickest near its junction with the cap at the point where a round aperture or a slot, C, is formed, through which passes one end of a spring, D, coiled 40 round inside the cap, which end catches into an annular groove in a stud, E. At F is shown a washer beneath the cap, forming an inclosure for the spring; but this washer may sometimes be dispensed with.

45 G is a washer for fastening the button to the material.

The stud E is provided with a base, H, having an overhanging rim, h, all around the same. At the junction of the stud and its base is an 50 enlargement, I, whose object will be herein-after explained. J shows an eyelet which is used to fasten the stud to the material K.

Having thus described all the parts, I will now proceed to describe the mode of uniting the same to the material.

In securing the stud a hole is made through the material in the usual manner, and after the stud E is passed through it the eyelet J is slipped over the shank of the stud, and is then pressed down by a suitable punch or other device, and 60 when the lower part of the eyelet strikes the enlargement I it is forced open and spreads, as shown in Fig. 1, until it extends outward under the rim h, which by the pressure of the punch is flattened down upon the lower part 65 of the eyelet, and thus the stud is securely fastened in place.

To secure the button top A the tube B is passed through a hole in the material, and a washer, if one is used, is placed on the lower 70 end of the same, when the force of a punch or other suitable instrument will clinch the lower part of the tube and spread it, as shown, and firmly secure the button top or cap to the material.

When in use, it is only necessary to press the button down over the stud, when the latter will enter the tube, and its point will push back the end of the spring D, which, when it reacts, will enter the annular groove in the 80 stud, and thus the button and stud will be securely fastened together against any ordinary strain. A sudden pull, however, in the proper direction will easily separate the button from the stud, and thus the glove or other object to 85 which the stud and button are attached may be fastened or unfastened with the greatest ease.

Instead of making the stud, base, and the rim all in one piece, as shown in Figs. 1 and 90 4, the stud may have a base of comparatively small diameter, and a cap, L, (see Fig. 7,) with an overturned flange or rim formed on its periphery, and the whole may be united by pressing on the eyelet, as shown in said Fig. 7. 95

It is of course obvious that the studs may be made solid or hollow, as desired; but I prefer them made hollow, as shown in Figs. 1 and 4, and where I refer to studs in the following claims I mean to include solid as well as hollow studs.

I am not aware that there has ever been used a single piece which contains as integral parts a cap or button-top and a clinching-tube,

which together constitute a whole piece in which one portion, as the cap A, is to be secured to the fabric or material, while the other portion, as the tube B, serves as a connected 5 and ready means for clinching the first-named portion to the material.

When the cap and tube are made separately, as has been proposed, and the stud is pushed into the tube, there is a tendency to 10 displace the tube, and unless it is very strongly fastened below, it will in course of time become loosened and be forced upward, and thus be made useless. This will not occur with mine, and, moreover, with my construction the 15 cap and tube may be used as a shirt-stud without being fastened to the cloth by leaving off the fastening-washers and simply using the parts shown in Figs. 3 and 4. If the corresponding parts in those buttons having the cap 20 and tube made separately were used in this way, said cap and tube would separate, and the button thus become useless. The other advantageous results obtained are, that the cost 25 of producing the single pieces A B will be very much less than that of separate caps and tubes, and the work and expense of assembling the separate pieces are wholly obviated, which is of great importance; and, further, the making 30 of the button-top proper and tube to compose a single piece enables the button to be more readily applied and secured to the material than where the cap and tube are separate parts; and, further, this solid union of the tube with the button proper prevents the 35 forming of an annular projecting surface around the central hole in the button-top, as is produced when the said top and tube are made separate.

In application No. 154,151, of even date here- 40 with, I show an enlargement at the junction of the base and stud, for the purpose of turning outward the base of the eyelet under spurs,

which spurs are obviously the equivalent of the flange *h* shown in this application, when used in connection with the enlargement and 45 eyelet before referred to, and as covered in claim 4 in this specification.

What I claim as new is—

1. In a separable button, the hollow cap and tube A B, formed integral, the hollow cap portion being the button-top proper, and the tube portion being the means for uniting the connected button-top with the fabric or a piece 50 on the fabric by clinching, substantially as and for the purpose set forth.

2. As an improved article of manufacture, a separable button consisting of a hollow cap and a tube both formed in one piece, a spring having its point projecting through the tube, the cap being adapted to receive and hold the 60 spring and the tube having a hole to receive the point of the same, and a slip-stud provided with an annular groove or notch, into which the point of the spring catches, substantially as described.

3. In a separable button, a tube perforated at its side to receive the spring and made of increased thickness around the tube near the perforation, substantially as and for the purpose specified.

4. A stud having a base provided with an inwardly-turned flange and an enlargement near the junction of the stud and base, constructed to deflect the fastening-eyelet toward the flange and under the same, substantially 75 as described.

In testimony whereof I affix my signature in presence of two witnesses this 24th day of January, 1885.

MADISON D. SHIPMAN.

Witnesses:

H. K. HELMER,
SAMUEL E. BRADT.
